Application August 17, 1948, Serial No. 44,649

12 Claims. (Cl. 250—27)

1

This invention relates to a method and apparatus for the removal of a beam of charged particles from a particle accelerator such as a cyclotron. It is particularly concerned with the extraction of high velocity ions from a frequency modulated type of cyclotron by means of electrostatic deflecting electrodes and magnetic-field neutralizing bars.

A detailed description of a conventional cyclotron will be found in U. S. Patent No. 1,948,384 granted to E. O. Lawrence on February 20, 1934, entitled "Method and Apparatus for the Acceleration of Ions." A means for withdrawing the ions from the magnetic field at a definite point in their circulatory paths has been described therein as consisting of a set of electrodes maintained at a suitable potential to draw the ions outwardly from the magnetic field. The ions are then drawn into a magnetic shield which serves to reduce the magnetic field intensity of the large magnetic poles sufficiently to allow the ions to deviate outwardly from the magnetic field by reason of their momentum. The above-mentioned ion accelerator employs a constant high frequency voltage for the acceleration of the ions in the magnetic field. As the orbits of the ions increase, the latter gradually get out of step with the radio frequency energy which is accelerating them, resulting finally in deceleration of the ions. Therefore, in such a type of ion accelerator, the accelerating voltage is made as high as possible in order that the maximum acceleration may be attained in the short time before the ions get out of phase with the accelerating force. The shorter accelerating time permits fewer orbits with relatively wide spacing or separation between successive orbits. Such wide spacing has permitted the use of a deflector to which was continuously applied a high D. C. voltage. When orbitally traveling ions come within the influence of the charged deflector, they are electrostatically deflected outwardly into a magnetic shield which thereby allows the ions to travel out of the influence of the magnetic field.

The co-pending application No. 748,434 filed May 16, 1947, Patent No. 2,615,129, issued October 21, 1952, by Edwin M. McMillan for a "Synchrocyclotron," makes use of a rotating capacitor to suitably vary the accelerating R. F. voltage whereby the ions remain in phase with their accelerating force. In this type of ion accelerator wherein the ions do not get out of step with the accelerating force, it is desirable that the ions travel as many orbits as possible in order that they may gain a maximum amount of

2

kinetic energy. This is accomplished by having the orbits of ion travel spaced as closely together as possible. Such close spacing as is accomplished in a synchro-cyclotron prohibits the use of the D. C. type of electrostatic deflector utilized in older type cyclotrons. With the orbits so closely spaced, the D. C. electrostatic deflector affects not only the desired orbit but also several of the adjacent orbits, thus making it difficult to remove ions of uniform energy.

The present invention is an electrostatic deflector which has a high voltage pulse applied to the deflector bars only when ions of a desired energy level are within the influence of the bars. This permits the withdrawal of ions at a maximum energy level without affecting any but the desired orbits.

The principal object of the present invention is to provide a method and an apparatus for removing ions from an electromagnetic ion accelerator.

Another object of the present invention is to provide a method and an apparatus for removing ions from only the desired orbit in an ion accelerator such as a synchro-cyclotron.

Another object of this invention is to provide a pulsed deflector electrode which functions only when the accelerated ions have reached a desired energy level.

A further object of this invention is to provide a magnetic field neutralizing means whereby the high energy ions may be extracted from the magnetic field of the ion accelerator.

A still further object of this invention is to provide a deflector system which is effective to remove ions of any desired energy from an ion accelerator.

Other objects and advantages of the invention will become evident by reference to the following detailed description in conjunction with the accompanying drawings wherein:

Fig. 1 is a simplified plan view showing the beam extractor and illustrating the theory of operation of the electrostatic deflector and magnetic shield thereof.

Fig. 2 is a one-line schematic diagram indicating the electrical components for the generation and formation of the pulses supplied to the electrostatic deflector.

Fig. 3 is a plan view partly diagrammatic of a cyclotron comparable to a cross section on a horizontal plane taken between the poles of the magnet.

Fig. 4 is an enlargement of a portion of Fig. 3 showing particularly the articulation of the electrostatic deflector and the means of apply-

ing the pulsed voltage to the electrostatic deflector bars.

Fig. 5 is a cross section taken on the vertical plane indicated by the line 5—5 of Fig. 4 and showing mechanical details of the pulse supply to the negative electrostatic deflector bars.

Fig. 6 is a cross section on a vertical plane indicated by the line 6—6 of Fig. 4 showing mechanical details of the pulse supply to the positive electrostatic deflector bars.

Fig. 7 is a vertical cross section taken on the plane indicated by the line 7—7 of Fig. 4 and showing the mechanical details of the linkage for adjusting the radius of the electrostatic deflector bars.

Fig. 8 is a cross section on a horizontal plane, indicated by the line 8—8 of Fig. 9, showing the radial articulation of the magnetic shield.

Fig. 9 is a cross section on a vertical plane indicated by the line 9—9 of Fig. 8 showing the mechanical details of the mounting of the shield bars and the field correcting shims.

Reference is now made to Fig. 1 which shows diagrammatically a beam extractor indicated generally by an arrow B and which includes an electrostatic deflector 1 having negatively pulsed bars 2, positively pulsed bars 3, and a magnetic shield 9. The electrostatic deflector 1 is curved to receive the final orbit of the accelerated particles indicated by a dashed line 4, and the particles are released from the deflector to travel a path indicated by a line of arrows 19 into the magnetic shield 9. Under the influence of a D electrode 12 and the magnetic field of magnetic poles (of which the lower pole 11 only is shown), the accelerated particles start with a point 5 as their radial center. This point precesses in a circle of precession 6 until the particles enter the electrostatic deflector when their radial center is changed to a point 7 and, subsequently, to a point 8 upon leaving the static deflector 1.

Referring to the block diagram of Fig. 2, a frequency modulated sine wave voltage is introduced through cable 39 to a manual pulse operation control 17 and to a trigger timing unit 18 through a current limiting resistor 14. The output of unit 18 is fed to an isolating trigger amplifier 19 and then to a high voltage pulse generator 23. The latter is charged by a high voltage power supply 21 through a shielded cable 15, a charging inductance 22, and a charging diode 23. Each unit has its own individual power supply fed from a common 120 volt A. C. line and insulated from the high voltage or charging diode 23 by a filament transformer 24. The theory of operation illustrated by Fig. 1 and the circuit for the formation of high voltage pulses Fig. 2 will be explained later in detail.

Reference is now made to Fig. 3 which illustrates a conventional frequency-modulated cyclotron utilizing my beam extractor, a pair of parallel D shaped electrodes 12, mounted in the magnetic field of a coaxial and spaced pair of magnet poles only the lower of which, 11, is shown, are enclosed within an evacuated chamber 28. The D electrodes 12 are supported in the chamber 28 by a pair of combination bushings and conductors 30 of a transmission line 32 which has as its outer conductor a metallic housing 31 containing a high frequency oscillator 35, the latter being frequency modulated by a rotary condenser 33 connected in the oscillator's transmission line 32. A variable-speed motor 34 drives the multi-bladed rotary condenser 33 at any desirable modulating frequency to compensate for the increasing orbits 75

of the accelerated particles. A loop 36 in the filament circuit and a loop 27 in the plate circuit of the oscillator are adjacent to the transmission line conductors 30 thereby coupling the oscillator voltage to the D electrodes 12. A small loop 37 extending into the transmission line 32 and having a collar 38 with a concentric cable 39 fitted into the wall of the metallic housing 31 may be rotated so as to pick up any portion of the magnetic flux cutting across the area enclosed by the loop 37. The voltage thus induced is used as the triggering voltage applied to the pulsed arc control unit 17 and the trigger timing unit 18 of Fig. 2 for the electrostatic deflector 1. An ion source 29 extending through a wall 13 of the evacuated chamber 28 releases ionized particles at the center of the magnet 11. A probe 42 protruding into the evacuated chamber 28 and slidably positioned by means of a probe extender 41 may be moved to intercept, and thereby sample, any orbit of the ionized particles during acceleration.

Attention is now directed to Figs. 4, 5, and 6 which show the structural elements of my improved beam extractor as utilized in the above-described frequency modulated synchro-cyclotron. The electrostatic deflector 1 consists essentially of a pair of negatively pulsed bars 2 and a pair of positively pulsed bars 3 arranged in a parallel arc of 120° which is preferably symmetrical with respect to the particle source 29 near the edge of the magnet pole 11 as best shown in Figs. 4, 5, and 6. A negative deflector bar support assembly 46 and a positive deflector bar support assembly 47 mounted on a horizontally movable base plate assembly 65 provide for the physical support of the bars 2 and 3 in space, their insulation from the base plate assembly 65, and the conduction of high voltage pulses from a high voltage pulse generator 20 (Fig. 2). As noted in Fig. 3, flexible metallic strap 44 connected between the negative deflector bar support assembly 46 and a negative pulse conductor 62, and a flexible metallic strap 45 connected between the positive deflector bar support assembly 47 and a positive pulse conductor 63 provide a flexible electrical connection from the conductors 62 and 63 to the electrostatic deflector 1. The two electrical pulse conductors 62 and 63 pass out of the hermetically sealed cyclotron chamber 28 through the cyclotron tank wall 26 by means of combination bushings and seals 42 and 43.

A set of control screws 48, 49, and 50 mounted on the walls 25, 26, and 13 of the cyclotron tank housing 28 are connected to their respective mechanical linkages 51, 52, and 53 which laterally position the electrostatic deflector movable base assembly 65.

The magnetic shield 9 (Figs. 8 and 9) consists of two slightly curved parallel iron bars mounted horizontally on a base plate 109 with one end inside the field of the magnet pole 11 and the other end of the magnetic shield 9 outside of the magnet pole 11. Two controls 54 and 55 (Fig. 3) mounted on the wall 26 of the cyclotron tank housing 28 and connected to their respective rotatable rods 58 and 59 rotate screws 56 and 57 which laterally adjust the position of a magnetic shield base plate 109 on which the magnetic shield 9 is mounted. An exit tube 60 having an hermetical aluminum foil seal 61 is welded on the cyclotron tank wall 26 in line with the magnetic shield 9 so as to allow the beam of particles to leave the cyclotron tank 28 after passing through the magnetic shield 9.

Referring now to Fig. 4, the deflector bars 2

and 3 of the electrostatic deflector assembly 1 are supported by several negative and positive deflector bar support assemblies 46 and 47 mounted on the movable base plate assembly 65 which is composed of articulated base plate sections 66, 67, 68, and 69. An articulating plate 70, connecting base plate sections 66 and 67 with bolts 73, has milled slots 74 so as to permit free lateral movement of the base plate sections relative to each other. Base plate sections 67 and 68 are articulately connected by an articulating plate 71 and a guide plate 76. Base plate 68 is hinged to the control screw mechanical linkage 52 which permits not only restricted articular motion but serves also to transfer the mechanical motion of the linkage 52 to the center base plate sections, as will be explained later. Control screw linkages 51 and 53 pivotally attached to base plate sections 66 and 69 provide for the transfer of mechanical motion to the outer base plate sections. The sectionalized deflector bars 2 and 3 attached to their respective deflector bar support assemblies 46 and 47 have sliding connectors 64 between bar sections in order to maintain electrical contact between the bars during radial and configural adjustments.

Referring now to Fig. 5, the negative deflector bars 2 are supported by an upper support rod 87 and a lower support rod 88 which are shaped so as to maintain a maximum clearance from the positive deflector bars 3 and are attached to a support fitting 86 on support cap 85. A porcelain insulator 84 bolted on the movable base plate section 67 bears and insulates from ground the support cap 85. Vertical adjustment supports 81 which slidably support the movable base plate assembly 65 are spaced at intervals under the movable base plate assembly and are pivotally bolted to the lower magnet pole 11 with a tilt adjusting bolt 83 on one end so as to vertically position the electrostatic deflector in the plane of beam rotation.

In Fig. 6 the positively pulsed electrostatic deflector bars 3 are supported by straight and parallel upper and lower support rods 89 and 90 of the positive deflector bar support assembly 47 and are clamped in place by upper and lower rod support plates 91 and 92. A porcelain insulator 94 bolted to the movable base plate assembly 65 rigidly supports a metallic cap 93 on which the rod support plates are mounted and on which the positive flexible connecting strap 45 is attached by means of a connection extension 95. All but two of the positive and negative deflector bar support assemblies 47 and 46 which are separately and laterally spaced along the movable base plate assembly 65 (Fig. 4) are for support only. The remaining centrally disposed two support assemblies serve also to apply the deflecting pulse from the high voltage pulse conductors 62 and 63 through flexible connecting straps 44 and 45 to their respective deflector bar support assemblies.

Referring now to Fig. 7, there are shown the operational details of the mechanical linkage controlling the movement of the center base plate sections of the electrostatic deflector. An articulating plate 71 (Fig. 4) which is rigidly bolted to movable base plate section 67 and pivotally bolted to movable base plate section 68 by means of a guide bolt 75 articulately joins the two center base plate sections. The electrostatic deflector control linkage 52, pivotally bolted to a corner of base plate section 68 by means of a pivot linkage bolt 78, serves to impart mechanical motion to base plate section 68. The guide bolt 75 has an elong-

gated round shank 100 adapted to slide along a guide plate slot 77 of a guide plate 76 which is rigidly bolted to the lower magnet pole 11 thereby insuring that both center base plate sections 67 and 68 will move radially with an equal and linear motion. A long connecting rod 102 (Fig. 3) coupled between the radial adjustment control screw 49 (Fig. 3) and the adjusting linkage 52 by means of levers 97 and 99 attached to a pivot 98 mounted on a square U type yoke 101 and bolted to the cyclotron tank wall 26, serves to transmit radial adjustments from the manual control screw to the center base plate sections.

The following description of the mechanical details of the structure of the magnetic shield is made with reference to Figs. 8 and 9. Rods 105 and 106, which are connected to position adjusting screws 51 and 56 (Fig. 3), terminate in pivotal connections 107 and 108 attached to the lower magnetic deflector base plate 109 and are adapted to move between lateral motion restraining guides 110 and 111 so as to position the magnetic shield with respect to the final radial center of orbitally accelerated particles. The backing plate 115, upon which is mounted the entire magnetic shield 9, is sustained by an upper base plate 112 and a lower base plate 109, both of which are strengthened by reinforcing plates 113 that serve to prevent the powerful field of the magnetic field of poles 11 and 114 from distorting or moving the shield. A group of shield-bar supports 116 and shield-bar support shims 120 rigidly bolt and laterally position, with respect to the backing plate 115, a pair of magnetic shield bars 118 and 119. Magnetic shims 121, supported by shim supports 117 and laterally spaced by shim spacers 122, are used to adjust the magnetic flux field in which shield bars 118 and 119 are to function. Auxiliary field adjusting shims 123, attached to the magnetic shims 121 by brace plates 124 and shimmed by brace plate shims 125, have reinforcing members 126 bolted to the brace plates 124 for rigidity. The auxiliary field shims 123, which are used for minor flux field adjustments, have coil springs 127 mounted on spring supporting rods 128 bolted between the brace plates 124. The free end of the springs 127 bear against spring push-plates 129 bolted to the auxiliary field shims 123 thereby normally urging the auxiliary field shims into a nearly horizontal position (as shown by the dotted lines of Fig. 9) to facilitate removal of the magnetic shield assembly 9. When the magnetic field is on, however, the magnetic force of the poles 11 and 114 is sufficient to overcome the spring force of the coil springs 127, and the auxiliary shims 123 maintain a vertical position.

Considering now the operation of the beam deflector in a particular particle accelerator, such as the 184 inch cyclotron, ionized molecular particles such as positively charged hydrogen ions (protons), deuterons, or alpha particles (positively charged helium ions) are released from the source 29 (Fig. 3). When released, these particles are at position 5 in the cyclotron (Fig. 1), but under the influence of the D electrode 12 and a perpendicular magnetic field due to poles 11 and 114 (Fig. 9), the particles leave the center 5 and commence to spiral around the circle of precession 6. The characteristics of cyclotron acceleration are such that, as the particles revolve at high speed, the locus of centers of rotation form a small circle 6, in this case about two inches in diameter, which is known as the circle of precession. The radial center performs one complete

precession for about every twenty orbital revolutions of the particles. The particles are formed into groups or bunches spaced twenty revolutions apart by pulsing the source 29 (Fig. 3) only once for each precession. As the particles revolve, a sinusoidal decrease of frequency of the high frequency voltage on the D electrode 12 allows the particles to spiral outwardly from the center 5 yet remaining in step with the accelerating voltage. The particles thus spiral outwardly in bunches spaced twenty revolutions apart until the beam enters the electrostatic deflector 1 at which time the radius of revolution is about 81½ inches. The deflector voltage is not applied until the radial center has precessed to about position 5 (Fig. 1) in order to obtain the optimum radial position. As the charged particles spiral into the deflector 1, a 200 kv. pulse which rises from ten percent to ninety percent of full voltage in 0.1 microsecond is applied to the deflector bars 2 and 3 causing the outer pair of bars 3 to become positive and the inner pair of bars 2 to become negative. The polarity of the deflecting pulse is such that it tends to push the outward spiraling particles back toward the source, constraining them to follow the curvature of the deflector 1. Since the deflector's radius of curvature is three inches less than the radius of curvature of the particles before entering the deflector, the radial center of the particles while in the deflector is shifted to point 7. The pulse which is applied just before the particles enter the deflector and removed just before the particles leave the deflector gives the ion particles a strong radial motion which is immediately opposed by the stability characteristics of the ions so that upon leaving the deflector field the ion particles tend to resume their original radius of curvature. Due to the angular change of position of the particles, however, the radial center 7 extends three inches to the point 8 which is along a line composed of the exit of the deflector 1 and the restrained radial center 7. The beam of ions now swings about point 8 as a center and moves along path 10 and out of the cyclotron field into the magnetic shield 9 which, by reducing the magnetic field in the path of the particles, guides the particles out of the cyclotron.

The ion particles which are generated in groups or bunches are separated sufficiently such that operation of the deflector influences but one group at a time. The deflector is operated only when the precession center is at position 5 in order to take advantage of the decreased distance of the radial center to the entrance of the electrostatic deflector. If the deflector were operated with the precession center opposite position 5, approximately two inches would be lost, and the ion particles might strike or entirely miss the magnetic shield 9.

Referring to Figs. 5 and 6, the outer bars 3 are pulsed positively and the inner bars 2 are pulsed negatively. As the positively charged ion particles travel along the length of the electrostatic deflector 1, they are repelled by the positive bars 3 and attracted by the negative bars 2 thus urging the particles inwardly toward the center. The deflector would also operate successfully if a "pusher" charge were used in the deflector bars 2 and 3. That is, if the inner members 2 were made positive and the outer members 3 were made negative during the pulse, the beam would be forced outwardly instead of inwardly. This method has the disadvantage of subtracting the radius of the precession circle 6 from the final radius of curvature so that if the precession

of the beam were sufficiently large, the beam might not get out at all. The maximum amount of deflection of accelerated particles is obtained with a deflector having an arc of 180°. A deflector 5 of less than 180° will not fully utilize the maximum possible outward shift of the radial center 7, whereas a deflector of more than 180° curvature will actually cause a recession of the radial center 7. In the present 184 inch cyclotron, a deflector having a curvature of about 120° is used to obtain satisfactory deflection and yet avoid physical interference with the D electrode 12.

After the ions leave the deflector 1 with their new radial center 8, they have gained a distance 15 away from the initial center 5 equal to the distance between points 5 and 8 or, as in the 184 inch cyclotron at the University of California, about 6½ inches. This distance is adequate to bring the ions within the influence of the magnetic shield 9 thereby lowering the circumferential magnetic force of poles 11 and 14 sufficiently to permit the ions to leave the magnetic field without disturbing any succeeding ion orbits. The magnetic shield 9 lowers the field strength of the 20 magnetic field to a value less than thirty percent of what the field would be without the shield. Shims 121 and 123 are placed directly in front of the magnetic shield 9 to compensate for the 25 change wrought in the magnetic field by the shield, thus permitting a uniform flux density up to the shield so as not to distort the orbits of the undeflected ions.

In order to remove ions of various energy levels, the electrostatic deflector 1 and the magnetic 30 shield 9 are adjustable laterally with respect to the center of the cyclotron 5. When it is desired to deflect particles of lower energy, controls 48, 49, and 50 are turned so as to move the deflector 1 toward the particle source. Controls 54 and 40 55 are also rotated so as to move the shield 9 inwardly. For ions of higher kinetic energy, the 55 controls for the electrostatic deflector 1 and the magnetic shield 9 are rotated to adjust them outwardly, thus intercepting ions of a higher speed and larger radius.

Referring again to Fig. 2, the function of the triggering and pulsing network will be briefly described. A more complete disclosure of the circuits and operation will be found in the co-pending applications of Quentin A. Kerns, No. 12,356 filed March 1, 1948, Patent No. 2,500,756, and No. 18,927 filed April 5, 1948, Patent No. 2,517,676. A frequency modulated voltage 39a varying between 9.5 and 11.8 megacycles and modulated by a 100 cycle per second voltage, is conducted directly to the pulsed arc control unit 17 and by means of the voltage limiting resistor 14 to the trigger timing unit 18. The pulsed arc control unit 17 generates a square-wave gate voltage 17a which is 90° out of phase with the F. M. wave 39a thereby permitting operation of the source 29 (Fig. 3) only on the downward or accelerating portion of the F. M. cycle. The deflector trigger timing unit 18 correlates the inputs of the 60 square-wave gate 17a and the F. M. wave 39a so as to generate a 300 volt deflector trigger pulse 18a of about 0.2 microsecond duration which is amplified by the trigger amplifier 19 to form a 65 500 to 1000 volt square-wave trigger pulse 19a. The high voltage pulse generator 20, consisting of a bank of high voltage capacitors fired by thyratrons, is triggered by the amplified trigger pulse 19a and delivers a positive 100 kv. pulse 20a which is applied to the outer deflector bar 3 and a negative 100 kv. pulse 20b which is applied to the 70 75

inner deflector bar 2 of the electrostatic deflector 1. The deflected particles passing between the positive and negative deflector bars 3 and 2 are, in effect, influenced by a 200 kv. pulse, since the positive and negative 100 kv. pulses applied to the bars 3 and 2 add to 200 kv.

The voltage for the operation of the deflector pulse generator 20 is generated by the high voltage power supply 21 which is adjustable from zero to 15 kv. The charging inductance 22, by means of the energy contained in its magnetic field, is able to supply half of the energy required every time the high voltage pulse generator 20 operates. Thus, the power supply 21, in charging its capacitors and the charging inductance 22, can supply twice the voltage for which it is set. The charging diode 23 prevents the double voltage of power supply 21 from leaking off until the high voltage pulse generator 20 is triggered. The shielded cable 15 serves to prevent its high flux field from inducing spurious voltages in associated wiring due to the high discharge currents present during pulse operation. The filament insulating transformer 24 serves to provide the proper filament voltage and current for the charging diode 23, yet preventing the high voltage of power supply 21 from arcing to the relatively low-voltage power source.

While I have described the salient features of this invention in detail with respect to one embodiment, it will, of course, be apparent that numerous modifications may be made within the spirit and scope of this invention. I do not therefore desire to limit the invention to the exact details shown except insofar as they may be defined in the following claims.

What is claimed is:

1. In a deflector for the removal of ionized particles from an electromagnetic type of ionized particle accelerator, a magnetic shield comprising a plurality of curved and spaced ferromagnetic bars arranged along the path of travel of said particles in the magnetic field of said accelerator to reduce the magnetic flux in the path of said particles, means for effecting lateral adjustment of said bars, and magnetic field correcting shims disposed above, below and in front of said bars to compensate for the magnetic field distortion due to the latter.

2. In a particle deflector for the removal of ionized particles from an electromagnetic particle accelerator of the cyclotron type, a magnetic shield for the reduction of a portion of the magnetic flux field of said accelerator comprising a plurality of spaced and substantially parallel ferromagnetic bars arranged near the outermost orbit in the plane of rotation of said particles to reduce the magnetic flux in the path of said particles, means for effecting lateral adjustment of said bars, and magnetic field correcting shims of magnetic material disposed above, below and in front of said bars to compensate for the magnetic field distortion due to said bars.

3. In an electromagnetic particle accelerator of the cyclotron type, an extractor for ionized particles comprising a plurality of electrostatically pulsed conductors disposed near the path of said particles to alter the radial center of said rotationally accelerated particles, and a magnetic shield disposed near the particle exit of said accelerator to guide said particles with the altered radial center out of the accelerator.

4. In an electromagnetic particle accelerator of the cyclotron type for the spiral acceleration of charged particles, a particle deflector compris-

ing a plurality of parallel spaced non-magnetic conductors formed into an arc not exceeding 180° arranged in the plane of rotation of said charged particles, a high-voltage pulsing means for applying a D. C. pulse of the same polarity as said charged particles to certain of said conductors and of opposite polarity to the remainder of said conductors to constrain said particles to follow the curvature of said conductors and thereby shift the radial center of said particles, and a plurality of parallel ferromagnetic bars arranged in the plane of rotation of said charged particles to lower the magnetic force in the path of said particles and positioned so as to receive those particles with said shifted radial center, thereby guiding said particles out of the particle accelerator.

5. In an electromagnetic particle accelerator of the cyclotron type for the spiral acceleration of charged particles, a particle deflector comprising a plurality of non-magnetic segmented conductors disposed in parallel spaced relationship and formed into an arc not exceeding 180° arranged in the plane of rotation of said charged particles, articulating means between said segmented conductors, means for adjusting the radius and the lateral position of said segmented conductors, high-voltage pulsing means for applying a D. C. pulse of the same polarity as that of said charged particles to certain of said conductors and of opposite polarity to the remainder of said conductors to constrain said particles to follow the curvature of said conductors thereby shifting their radial center, a plurality of parallel ferromagnetic bars arranged in the plane of rotation and at the outermost orbit of said charged particles to weaken the magnetic field and guide said charged particles out of said particle accelerator, means for laterally adjusting said bars, and magnetic field correcting shims disposed above, below and in front of said bars to compensate for the magnetic field distortion due to the latter.

6. In an electromagnetic particle accelerator for the spiral acceleration of ionized particles, a particle deflector comprising a plurality of arcuately shaped, adjustably spaced, conductive deflecting bars disposable along an outer orbit of said ionized particles, electrostatic pulsing means connected to said bars for altering the radial center of said particles during the interval that said particles are in said outermost orbit, and means for adjusting the position of said deflecting bars relative to any selected particle orbit.

7. In an electromagnetic type of particle accelerator having a particle deflector for the removal of ionized particles therefrom, an adjustable magnetic shield comprising a plurality of arcuately shaped ferromagnetic rods arranged along the exit path of said particles to reduce the intensity of magnetic flux in the path of said particles, lateral rod positioning means for effecting adjustment of the position of said rods, and magnetic field correcting shims disposed above, below, and in front of said rods to compensate for the magnetic field distortion due to the latter.

8. In a particle deflector for the removal of positively charged particles from an electromagnetic particle accelerator of the cyclotron type, a magnetic shield for the reduction of a portion of the magnetic flux field of said accelerator comprising a pair of arcuately shaped, ferromagnetic bars horizontally disposed side by side in spaced relationship along an outer orbit in

11

the orbit plane of said particles, field correcting shims above and below said bars, auxiliary field correcting shims above and below and in front of said bars, said auxiliary shims being held in correct vertical alignment by the magnetic field of said accelerator, and means for effecting lateral adjustment of said bars, shims, and auxiliary shims whereby the same may be positioned to provide maximum neutralization of the magnetic field of the particle accelerator in the path of the extracted particles.

9. In an electromagnetic particle accelerator of the cyclotron type, an extractor for ionized particles comprising a support mounted in the magnetic field of said accelerator and laterally adjustable in a plane which is normal to said field, a plurality of spaced electrical conductors mounted in insulated relation upon said adjustable support, said conductors having similar curvature and coinciding with a portion of an outer orbit of said particles, high voltage electrostatic pulsing means connected to said conductors for energizing the latter and deflecting said particles, and an adjustable magnetic shield disposed near the particle exit of said accelerator whereby particles deflected by said pulsed conductors are guided out of said accelerator by said magnetic shield.

10. In an electromagnetic particle accelerator of the cyclotron type, an extractor for ionized particles comprising a first laterally adjustable support mounted in the magnetic field of said accelerator, a plurality of parallel electrical conductors mounted in insulated relation on said adjustable support, said conductors extending arcuately for less than 180° of an outer orbit of said particles and coinciding with said outer orbit, high voltage electrostatic pulsing means connected to said conductors for deflecting said particles, a second laterally adjustable support mounted in the magnetic field of said accelerator, and a magnetic shield consisting of a pair of substantially parallel ferromagnetic bars attached to said second adjustable support and disposed near the particle exit of said accelerator

12

for guiding said accelerated particles out of said accelerator upon energization of said conductors.

11. In a frequency-modulated cyclotron having a spaced pair of magnet poles, a pair of D shaped electrodes therebetween and a surrounding evacuated chamber, and a frequency-modulated oscillator coupled through a transmission line to said D shaped electrodes, the combination comprising a particle deflector having a plurality of arcuately shaped, adjustably spaced, conductive deflecting bars disposable along an outer orbit of particles accelerated by said cyclotron, electrostatic pulsing means connected to said bars for altering the radial center of said particles during the interval that said particles are in said outer orbit, and a coupling loop connected to said pulsing means and adjacent said transmission line for triggering said means.
12. The combination of elements set forth in claim 11 wherein said transmission line includes a pair of insulated conductors supporting said D shaped electrodes and a surrounding metallic housing, and said coupling loop is rotatable to vary the flux cutting thereacross.
